UNITED STATES PATENT OFFICE.

ARCHIE H. BECHTOL, OF DAYTONA BEACH, FLORIDA, AND WALTER A. TRATSCH, OF CHICAGO, ILLINOIS.

DESIGN FOR A BILLIARD TABLE OR SIMILAR ARTICLE.

Application filed October 13, 1927. Serial No. 23,746. Term of patent 14 years.

To all whom it may concern:

Be it known that we, ARCHIE H. BECHTOL and WALTER A. TRATSCH, both citizens of the United States, residing at Daytona Beach, Florida, and Chicago, Illinois, respectively, have invented a new, original, and ornamental Design for a Billiard Table or Similar Article, of which the following is a specification, reference being had to the accompanying drawing, forming part thereof.

Fig. 1 is a side elevation;

Fig. 2 is an end elevation; and

Fig. 3 is a partial top plan view.

We claim:

The ornamental design for a billiard table or similar article as shown.

In testimony whereof we affix our signatures.

ARCHIE H. BECHTOL.
WALTER A. TRATSCH.
